UNITED STATES PATENT OFFICE.

GUIDO MARCHESI CHIERICATI, OF NEW YORK, N. Y.

DESIGN FOR A CLOCK-DIAL.

SPECIFICATION forming part of Design No. 34,162, dated March 5, 1901.

Application filed December 26, 1900. Serial No. 41,171. Term of patent 7 years.

To all whom it may concern:

Be it known that I, GUIDO MARCHESI CHIERICATI, a subject of the King of Italy, residing at New York, county of New York, and State of New York, have invented and produced a certain new and original Design for Clock-Dials, fully described and represented in the following specification and the accompanying drawing, forming a part of the same.

10 In the accompanying drawing the figure shows the clock-dial in front elevation.

The dial is in the form of a table-plate, having a center A, surrounded by a rim or flange B. This rim or flange B bears representations of the coats of arms of a number of different countries. The purpose of the design is to produce an ornamental plaque which at the same time shall be a clock-dial, the

plaque serving as a souvenir of a fair or exhibition.

20 The leading feature of the design consists of a clock-dial in the form of a plate such as described, bearing a series of coats of arms on the flange thereof.

Having described my invention, what I claim as new, and desire to secure by Letters Patent, is—

25 The design for a clock-dial substantially as herein shown and described.

In testimony whereof I have hereunto set my hand this 22d day of December, 1900, in the presence of two witnesses.

GUIDO MARCHESI CHIERICATI.

Witnesses:

H. J. RUFFINO,
ENRICO BUDONI.
